UNITED STATES PATENT OFFICE.

ELMER R. EDSON, OF PORTLAND, OREGON.

RAILWAY SWITCH.

Application filed April 18, 1927. Serial No. 184,687.

My invention relates to my United States Patent Number 1,612,271, issued to me under date of December 28, 1926, for a railway track and rail; my invention also relates to 5 patent applications filed concurrently here- with, two in number, one upon a new and improved switch, Serial No. 184,686, and the other upon railway road bed and track construction, Serial No. 184,685.

10 My present invention relates to a switching device adapted more particularly for use upon a railway track wherein a guide wheel is associated with the rail to prevent the jumping of the track of the vehicle with 15 which the support and guide wheels are associated when the same are propelled at fairly high speeds, and consists primarily of hinged elements which are adapted to alignment with the main line of the railway 20 and which are also adapted to being moved laterally to permit of the same meeting in alignment with the side track or switch line.

25 The primary object of my invention is to provide a suitable mechanism for switching trains adapted to rapid transit, as evidenced in my patent and applications therefor aforesaid.

30 A further object of my device consists in moving but one end of the switch laterally, the other end being in hinged relationship 35 with the rails of the main line, thus preventing the necessity of forming frogs or cross-overs which distort and cut away much of the supporting element of the rail struc- 40 ture upon which the vehicle to be propelled thereupon engages.

45 A still further object of my invention resides in providing alignment devices that are precise in the positioning of the rail structure, which makes it possible to propel vehicles and trains therealong at relatively high speeds.

50 A further object of my invention consists in providing a section of the main line that may be moved at one end into engagement with the side track or switching track, means being provided to automatically raise one of the rails of the side track to permit of such connection and to maintain the precise alignment of the switched portion of the main line with that of the side track or switching track.

55 A still further object of my invention consists in providing hinged relationship of the

cross connecting elements of the main line rails and supporting beams to maintain the same in substantially the same spaced relationship during such switching operation.

60 And still further objects of my invention consist in providing new and novel and useful means for locking the switching portion of the main line in placed position.

65 With these and incidental objects in view, the invention consists in certain novel features of construction and combination of parts, the essential elements of which are set forth in the appended claims, and a preferred form of embodiment of which is hereinafter shown with reference to the drawings which accompany and form a part 70 of this specification.

In the drawings:—

Fig. 1 is a top plan view, partially in section, of the switching portion of the main line track shown in position relative to the 75 main line.

Fig. 2 is a top plan view, of the mechanism, illustrated in Fig. 1, showing the switch thrown for engagement with the side 80 track or switching track.

Fig. 3 is an end sectional view, taken on line 3—3 of Fig. 1, looking in the direction indicated.

Fig. 4 is an end sectional view, taken on line 4—4 of Fig. 1, looking in the direction 85 indicated, the same being made to illustrate a preferred embodiment of the mechanism for the lateral movement of the switching portion of the main line section.

Fig. 5 is a sectional side elevation, taken 90 on line 5—5 of Fig. 2, looking in the direction indicated, the same being a detailed view of the automatic mechanism for lifting a hinged element of one portion of the rail of the switching or side track, the same also 95 illustrating the trunnion support for the main line switch section.

Fig. 6 is a fragmentary side elevation, taken on line 6—6 of Fig. 1, looking in the direction indicated.

Fig. 7 is a top plan view, taken on line 7—7 of Fig. 6, looking in the direction indicated.

Fig. 8 is a fragmentary top plan view, 105 partially in section, of the hinge disposed in the rail section of a side track or switching line.

Fig. 9 is a fragmentary end view, of the

preferred embodiment of the locking device for locking the main line rails, or the switching line rails, in precise placed position.

Like reference characters refer to like parts throughout the several views.

1 and 2 are the main line rails, and 3 and 4 are the switching rails of the main line which are in hinged relationship therewith.

I have found that best results are obtained wherein the hinged position of the hinging rails are not in the same line relative to a right angle drawn between the two main line sections, as each hinging center should be an equal distance from the line illustrated at 5 in Fig. 1. These rails are in hinged relationship, as illustrated in Fig. 6, wherein web sections of beams 7 and 8 forming the structural support for the rails 2 and 4 are cut away to permit of a forming of the bearing 9 and 10 of the flange sections of the beams, one member of each section being off-set to permit of its engagement with the oppositely disposed flange of the adjacent member with journal pins 11 and 12 being placed therethrough to form a hinged joint between the beams 7 and 8. The rail sections 1 and 3 are hinged together as illustrated in Fig. 7, wherein the rail section 3 which is secured to the beam 8 and the rail section 1, which is secured to the beam 7 are in hinged relationship by having the under section of one concave and the oppositely disposed engaging end section convex to form a working relationship between the rail sections without the undue longitudinal cutting of the bearing or wearing section of the rail. The cross support 13 connecting the longitudinal beams of the supporting rails 3 and 4 is journaled about journal pins 14 and 15 each of which operates within bearings 16 and 17 of the terminal end sections 18 and 19 that are directly secured to the main longitudinal beam sections by any suitable fastening means, as by being riveted thereto. Because of the hinging of the rail sections to the supporting cross beam, relative to the main line, there will be a tendency for the rail sections to vary in relative distances apart laterally during lateral movement. The cross beam 13 should be so placed as to compensate for this change in distance. The angle to which the switch opening is made relative to the main line should be made relatively small to obviate this difficulty. While there will be a slight difference in spaced relationship of the rails during the movement of the switch the placed position can be made to conform to the original spacing when the switching section is in the main line, and by so doing the switch elements can be made to work satisfactorily for the purpose intended. A multiple of supporting tracks 20, 21, 22 and 23 are provided upon which trunnion wheels are made to engage, as illustrated at 24 in Fig. 5. These

trunnion wheels should be of sufficient length to give a full bearing upon the supporting rail 23, disposed thereunder. The trunnion wheels are mounted upon shafts that operate within bracket bearings 26 and 27. The rack 28 is secured to the beam 8 and passes through the gear box 29. Disposed within the gear box 29 is shaft 30 having secured thereto a pinion in registerable alignment with the rack 28. The shaft pinion and the rack being operated and positioned through the manipulation of the hand wheel 31.

During the manipulation of the switch track section, and the positioning of the same through the operation of the associated elements comprising the gear rack and the pinion, it is necessary to raise the rail section 32 to clear the same when operated. The same is accomplished by the mechanism illustrated in Fig. 4 and in Fig. 5, wherein the shoe 33 contacts with the push rod 34 and depresses the same against a compression spring 33^A disposed thereabout. As the push rod 34 contacts with the lever 36 journaled about the cross shaft 37 the oppositely disposed end of the lever 36 is raised and the link 38 connecting the outwardly disposed end of the lever 36 and the rail section, with which it is in hinged relationship raises the rail section 32 about the journal 39. After the rail section 4 has passed the hinged rail end 32 the shoe 33 passes over the compression rod 34 and the hinged rail section 32 is permitted to return to its normal depressed position. After the track unit has been approximately positioned, the shaft 43 having disposed thereupon two positioning shoes 41 and 42, as illustrated in Fig. 9, are turned up to engage the under side of the longitudinal beams and position the same into precise alignment. The shaft 43 upon which the shoes 41 and 42 are positioned is operated through the hand operating lever 44 secured to the shaft 43.

Should it be desired to raise the hinged rail section 32 for any reason, when the shoe 33 is not contacting with the compression element 34, the overrotation of the lever 44 and the shaft 43 associated therewith, will cause the lug 45 to engage the lift link 46 and to engage the projecting pawl 47 on the upper end thereof and will raise the lever 36 and the hinged rail section 32 hingedly secured thereto; this mechanism is illustrated in detail in Fig. 5.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, the combination of a main line track and a switch line track, a switching section of track disposed normally in the main line of track, one end of each rail section of switching track being hinged to the rail section of the main line, one end of the switching section being adapted to lateral movement to permit registerable alignment with the rail sections of the switching track, trunnion supporting wheels for the switching section, rail supports for the trunnion wheels, a rack disposed outwardly from one side of the switching section, a pinion associated with said rack and means for actuating the pinion. 45
2. In a device of the class described, the combination of a main line track and a switching track, a switching section of track disposed within the main line track and hingedly secured thereto by each rail section of one end of the main line track being hinged to the oppositely disposed ends of the switching track, means for imparting a lateral movement to one end of the switching track section and means for raising and lowering one rail section of the switching track. 50
3. In a device of the class described, the combination of a switching track section of a railway being hingedly disposed relative to the main line track of a railway, means for imparting a lateral movement of one end of the switching track section, to substantially align the same with the switching track and means for a precise positioning of the switching track section consisting of a horizontal shaft having shoes positioned thereupon and means for rotating the shaft to cause the shoes to engage the underside of the rail supports of the switching track section. 55
4. In a device of the class described, the combination with a main line railway track and a switch line track, of a switching section of track normally disposed, as a bridge, to fill in a break or gap in the main line tracks, the rails of said switching section being hinged at their fulcrumed ends to the main line rails, and being adapted for lateral movement at their free ends to afford alignment with the rails of the switch line track, the spacing of the movable ends of the rails of the switching section being regulated by a pivotally mounted spacing beam disposed transversely between the rails, said spacing beam being set at such an angle to the rails that the distance between their movable ends will be the same, when moved into position for switching operations, as it was when the switch rails were set in alignment with the rails of the main line track. 60
5. In a railway switch, the combination with a main line track and a switch track, of a switching section provided within the main line track having one end thereof adapted for lateral movement into alignment with the aforesaid switch track, including means for accomplishing such movement, and means for raising an end of one of the rails of the switch track out of the line of movement of the switching section, which comprises a vertically rockable end section provided for said rail, a pivoted lever including a link connecting said lever to said end section, a push rod adapted for 65 rocking the aforesaid lever, and a shoe carried by the switching section adapted for contacting with and depressing said push rod when such switching section is moved laterally as aforesaid. 70
6. A railway switch as claimed in claim 5 including means for locking said switching section against movement, and means cooperating with the latching means for raising the aforesaid end section independently of the aforesaid shoe and push rod means. 75
